(57) **CLAIM**

The ornamental design for a hanging ornament, as shown and described.

DESCRIPTION

FIG. 1 is an isometric view of a hanging ornament showing my new design;

FIG. 2 is a first side elevation view thereof;

FIG. 3 is a second side elevation view thereof;

FIG. 4 is a third side elevation view thereof;

FIG. 5 is a fourth side elevation view thereof;

FIG. 6 is a top plan view thereof; and,

FIG. 7 is a bottom plan view thereof.

The broken lines shown in the drawings represent portions of the hanging ornament that form no part of the claimed design.

1 Claim, 6 Drawing Sheets(56)
